(57) **CLAIM**

The ornamental design for a ballast plow, as shown and described.

DESCRIPTION

FIG. 1 is a right side view of the ballast plow of the present invention, as it may be mounted on a Railroad Hopper Car.

FIG. 2 is a top left front isometric view of the ballast plow of FIG. 1;

FIG. 3 is a bottom right front isometric view of the ballast plow of FIG. 1;

FIG. 4 is a top right rear isometric view of the ballast plow of FIG. 1;

FIG. 5 is a top view of the ballast plow of FIG. 1;

FIG. 6 is a bottom view of the ballast plow of FIG. 1;

FIG. 7 is a front view of the ballast plow of FIG. 1;

FIG. 8 is a back view of the ballast plow of FIG. 1;

FIG. 9 is another right side view of the ballast plow of FIG. 1; and,

FIG. 10 is a left side view of the ballast plow of FIG. 1.

In FIG. 1, the broken lines depict environmental subject matter only and form no part of the claimed design.
